UNITED STATES PATENT OFFICE.

JOHN CHOMA, OF PITTSBURGH, PENNSYLVANIA, ASSIGNOR OF ONE-HALF TO BASIL MERENKO, OF PASSAIC, NEW JERSEY.

AUTOMATIC WARDROBE.

1,308,333.

Specification of Letters Patent.

Patented July 1, 1919.

Application filed April 17, 1918. Serial No. 229,025.

To all whom it may concern:

Be it known that I, JOHN CHOMA, a subject of the Emperor of Austria, residing at Pittsburgh, county of Allegheny, and State 5 of Pennsylvania, have invented certain new and useful Improvements in Automatic Wardrobes, of which the following is a specification.

This invention relates to improvements in 10 locks and particularly to types adapted to be applied to wardrobes, bath houses, toilets, and the like, which are operable by the insertion of a coin, co-incident with a proper key.

15 The principal object of the invention is to provide a lock, the bolt of which is normally maintained in a forward or locked position, and not permitting the bolt to be retracted except upon the entrance of a 20 proper coin.

A further object is to provide a dial or target, designating whether or not the apartment is in use, which is exhibited co-incident with the operation of the bolt, and to 25 further provide means whereby upon the insertion of a proper coin the bolt becomes amenable to the action of the key.

These and other like objects are attained by the novel construction and combination 30 of parts hereinafter described and shown in the accompanying drawings, forming a material part of this specification, and in which:—

Figure 1 is a front elevational view showing a series of wardrobes, or the like, and indicating the application of the invention.

Fig. 2 is an enlarged vertical sectional view taken through the lock.

Fig. 3 is an enlarged front elevational 40 view of a single wardrobe or compartment, parts being broken away in order to show the application of the invention.

Fig. 4 is a vertical sectional view taken on line 4—4 of Fig. 2, and

45 Fig. 5 is an enlarged transverse sectional view taken on line 5—5 of Fig. 3.

In the drawings, the numeral 10 indicates the base of a series of wardrobes or the like, over which extends a ceiling 11, 50 end walls 12, and partitions 13 between which are pivoted the doors 15, the pivots 16 being arranged centrally of the doors at the top and bottom thereof and consisting of cylindrical projections, in the upper 55 of which is engaged the inner, bent end of

a spiral spring 18, secured by a screw or like fastening 19, within a recess 20 in the ceiling 11, the arrangement of the spring being such as to normally maintain the door in a closed position at all times. 60

In the upper portion of the doors 15 is an opening 22, covered by a slide 23 movable between fixed guides 24 secured to the inner surface of the door, the slide bearing any desired designation as "Free" or numerals 65 representing the number of the particular compartment.

This slide is operated through a bar 25 engaged at its lower end with the slotted long arm 26 of a bell-crank lever pivoted on 70 the interior of the door by a pin 27, the opposite end 28 of the lever being engaged with an extending end 29 of the lock bolt so that as the latter is operated the slide is moved vertically within its guides, 75 indicating upon its face whether or not the compartment is in use.

The bolt mechanism comprises a casing 30 in which is slidably engaged a horizontal bolt 31, urged normally rearward by a 80 tension spring 32, secured at one end rigidly within the casing and at the other end to a portion of the bolt. An angular extension 33 is formed at the end of the bolt, connecting with the extension 29 and containing a 85 slot 34 slidable upon a fixed pin 35 by means of which the bolt is guided. The front end of the bolt engages normally, when in a locked condition within a keeper 37 fixed in the partition 13. 90

Formed integral with the connecting element 33 is an angular lug 38 engageable with the front end 39 of a bell-crank lever pivoted on the pin 40, the longer arm 41 of the lever extending slightly toward the 95 front and being formed into a cup 42, the bottom 43 of which is pressed upward by the flat spring 44, so as to make contact with the lower end of a rectangular tube 45, the tube being secured by the flanges 46 to 100 the upper portion of the lock casing 30 through which extends an opening 47 adapted to receive a coin of the proper denomination. The coin, passing downward through the tube 45, drops upon the bottom 43 of the 105 cup, its weight liberating the short arm 39 of the bell-crank lever and permitting the bolt to be moved rearwardly by the spring 32.

In order to close the slot against the insertion of a coin when the bolt is retracted, an 110

arm 50 is secured to the bolt, the same having an inturned upper end 51, enterable through an opening formed in the edge of the coin tube 45, so as to partially close the 5 opening therethrough, while upon the opposite side of the tube pivoted to the bolt 31 by the pin 53 is a lever 54, fulcrumed on the pin 55, its upper end engaging by the pin 56 with a sliding element 57 which, operating 10 in conjunction with the element 51 prevents insertion of a coin when the bolt is retracted.

When the coin has passed the cover plate 43, at the lower end of the coin tube, it 15 enters a compartment 60 formed in the bottom of the lock casing, and passes from there through a passage 61 to a coin drawer 62, from whence it may be recovered by one having the proper key thereof.

20 To prevent the insertion of spurious coins or the like, a guard 64, with its lower flange 65 is secured to the top of the lock casing 30 the same being arranged so that coins passed into the body thereof may drop 25 freely into the tube, while larger articles are prevented from being entered.

Arranged below the main bolt 31 at the front end thereof, is a block 70 having a recess 71, containing a compression spring 72, 30 pressing against the head 73 of a plunger 74, resting against the interior of the lock casing 30, immediately below the bolt. A lug 75 formed integral with the block 70 is contractable with the key 76 so that as the 35 key is entered and turned therein, it will cause the block 70 to move.

A lever 80, pivoted on a projecting pin 81, is pivotally engaged at one end with the block 70 and at the other end with the bolt 40 31, so that as the key is turned and the block projected outwardly, the bolt is caused to move by reason of the lever 80 in an opposite direction, so as to be wholly retracted

from the keeper 37, permitting the door to be unlocked.

It is to be noted however, that unless a coin has been inserted, and the arm 39 of the bell-crank lever removed, the key will be ineffective in operating the bolt. In operation, a coin having been inserted through the 50 opening 47 and the key entered in the usual manner, it causes the bolt to move rearwardly, thereby permitting the door to be opened, simultaneously moving the plate 23 into position to indicate that particular compartment is being used, at the same time the rearward movement of the bolt closes the coin opening, preventing the insertion of other coins until the compartment has again been locked.

Having thus described my invention what I claim as new and desire to secure by Letters Patent, is.

In a lock of the character described, a casing, a bolt slideable in said casing, a bell-crank lever pivoted in said casing, having its shorter arm secured to an extension of said bolt, its longer arm formed with a cup adapted to form the bottom of a coin chute, a spring for retracting said bolt upon the 70 operation of said longer arm of the bell crank lever by a coin, an arm secured to the upper edge of said bolt having an inturned upper end adapted to enter through an opening into the coin chute, a lever pivotally secured intermediate its ends to said casing, and with its lower end pivotally secured to the upper edge of said bolt, a sliding element pivoted to the upper end of said lever and adapted to enter said coin chute opposite to said inturned upper end of said arm, and means for retracting said bolt after its 75 operation.

In testimony whereof I have affixed my signature.

JOHN CHOMA.
